UNITED STATES PATENT OFFICE

105,663

DESIGN FOR A BEDSTEAD

Leo Jiranek, New York, N. Y., assignor to Heywood-Wakefield Company, Gardner, Mass., a corporation of Massachusetts

Application July 6, 1937, Serial No. 70,262

Term of patent 3½ years

To all whom it may concern:

Be it known that I, Leo Jiranek, a citizen of the United States and a resident of New York, county of New York, and State of New York, have invented a new, original, and ornamental Design for a Bedstead, of which the following is a specification, reference being had to the accompanying drawing, forming a part thereof, in which Fig. 1 is a perspective view of a bedstead showing my new design and Fig. 2 is a fragmentary detail sectional view on the line 2—2 of Fig. 1, but on an enlarged scale with respect to Fig. 1.

I claim:

The ornamental design for a bedstead substantially as shown.

LEO JIRANEK.
